UNITED STATES PATENT OFFICE.

ARTHUR THOMAS COLLIER, OF ST. ALBANS, ENGLAND, ASSIGNOR TO
THE REILLOC TYRE COMPANY LIMITED, OF LONDON, ENGLAND,
A CORPORATION OF GREAT BRITAIN.

ELASTIC TIRE.

No. 826,405.

Specification of Letters Patent.

Patented July 17, 1906.

Application filed September 7, 1905. Serial No. 277,435.

To all whom it may concern:

Be it known that I, ARTHUR THOMAS COLLIER, a subject of the King of Great Britain, residing at St. Albans, Herts, England, have invented certain new and useful Improvements in and Relating to Elastic Tires for Vehicles, of which the following is a specification.

This invention relates to elastic vehicle-tires built up of short lengths which can be conveniently renewed separately and which can nevertheless be securely held in position during use.

According to the present invention the tire is made in short lengths which are vulcanized to rigid carriers with one or more intermediate layers of india-rubber of greater hardness between the elastic india-rubber and the carriers, which are preferably secured in position on the wheel so that their longitudinal axes lie transversely to the plane of the wheel—that is to say, transversely to the plane extending through the center line of the tread, either at right angles or obliquely thereto.

According to one form of carrying the said invention into practice the short lengths of elastic material are mounted on rigid plates, which are secured in position on the wheel rim or felly by parts thereof projecting beyond the elastic material and engaging with grooved flanges secured to the sides of the said felly. In some cases these projecting parts of the rigid plates are supplemented by pins or projections formed by the ends of rods or wires extending through the elastic material, these pins or projections engaging with holes or recesses provided in the lateral flanges. Where a sufficient number of rods or wires are employed, the plates themselves may be dispensed with. One or both of the said grooved or recessed lateral flanges are preferably made detachable.

According to another constructional form of the said invention the rigid plates bearing the lengths of elastic material or the said lengths of elastic material themselves are provided at their inner or lower parts with dovetailed or like grooves or projections, which respectively coact with corresponding projections or grooves on or in the wheel-felly, these plates or lengths of elastic mate-

rial being secured in position laterally by suitable flanges.

In a further constructional form of the said invention the lengths of elastic material forming the tire are secured in position on the wheel rim or felly by means of screw-threaded studs or bolts which extend through holes in the wheel rim or felly and engage in screw-threaded holes provided in the rigid plates, or the tire lengths may be attached to the wheel by rings provided with screw-threaded shanks extending through holes in the felly and secured by nuts or the like, the rods or wires extending through the elastic material being threaded through the said rings.

The lateral surfaces of the short lengths of elastic material are preferably arranged to press against each other at their lower or inner parts, so as to reduce the internal stresses in the india-rubber or like material, the said surfaces being formed in such a manner that a series of grooves are produced around the tread of the tire. The lengths of elastic material are preferably arranged obliquely on the wheel-rim in such a manner that the oblique grooves formed between them extend in opposite directions on the wheels on opposite sides of the vehicle to prevent slipping sidewise of the said vehicle.

In the accompanying drawings, Figure 1 is a perspective view of part of a tire and wheel-rim constructed in accordance with one form or modification of the present invention. Fig. 2 is a plan thereof, and Fig. 3 is a section on the line xx , Fig. 2. Fig. 4 is a perspective view of a single length of tire, and Fig. 5 is a plan thereof. Fig. 6 is a perspective view of a single length of tire, illustrating a modified arrangement. Figs. 7, 8, 9, and 10 are sectional views of lengths of tires, illustrating modified arrangements for securing the same to wheel-rims. Fig. 11 is a perspective view illustrating a still further modification of my invention.

Referring to Figs. 1 to 5 of the accompanying drawings, aa are short lengths of elastic material mounted on rigid plates b , which are preferably arranged obliquely on a wheel-rim, the elastic material being so shaped that oblique grooves are formed between adjacent lengths of tire. Parts c of

the plates *b* project beyond or outside of the elastic material and engage in grooves *d*, formed in the flanges *e*. One or both of these flanges may be made detachable from the wheel-rim *f* and may be secured thereto — for example, by bolts *g*. The base portions of each length of tire may be extended to form ribs *h* lying in grooves *j*, formed in the sides of the hollow central portions *k* of the plates *b*. Wires or rods *m* are embedded in the ribs *h*, and the ends of these wires or rods project beyond the elastic material and enter holes *n* in the flanges *e*. The said wires or rods may be straight from end to end and enter oblique holes in the flanges; but preferably the ends thereof are bent, as more clearly shown in Figs. 2 and 5. The short lengths of elastic material may be formed with layers of textile fabric *o* embedded therein, (see Fig. 4,) the said layers converging toward and wrapping around the wires or rods *m* embedded in the material. If desired, in cases where wires or rods *m* are used in combination with a core *k* transverse wires or stays may be employed which extend through transverse holes in the said core and unite the wires or rods *m* on the opposite sides thereof, thus further increasing the strength of the tire.

In the arrangement shown in Fig. 6 a plate *b'*, formed in one sheet of uniform thickness, is shown in substitution for the plate *b*, having a raised central portion *k*. This plate *b'* supports a length of elastic material *a'* and is curved to conform to the cylindrical surface of the wheel-rim on which it is to be mounted. Projecting parts *c'* of the plate are arranged to engage the flange-grooves *d*, and wires or rods *m* are embedded in the elastic material, as in the form illustrated in Figs. 1 to 5. These wires may, however, be dispensed with. The elastic material may be soft india-rubber vulcanized to the supporting-plate with or without one or more intermediate layers of india-rubber of greater hardness, the layer nearest the supporting-plate preferably consisting of vulcanite suitably prepared to insure firm adhesion thereof to the material — *e. g.*, metal — of which the said supporting-plate is formed. The differences in hardness of the several layers are preferably obtained by making them of india-rubber mixtures of different compositions.

In the constructional form illustrated in Fig. 7 the rigid plates *b''* are formed with projections *p* undercut to slide between the undercut projections *q* on the rim. This arrangement secures the tire length both radially and circumferentially, the lateral retention being effected by side flanges similar to the flanges *e* in Fig. 1. The groove *d*, however, is not required in this instance, but holes are provided for the said flanges to receive the ends of the wires *m*. In some cases

in order to enable the grooves between the projections *q* on the rim to be made of a uniform depth the peripheral surfaces of the said projections may be concave in cross-sections taken on planes containing the axis of the wheel. A modification of this arrangement is illustrated in Fig. 8, in which the elastic material *a''* is forced into channel-shaped supporting-plates *b'''* or molded therein, and the said plates *b'''* are secured by rivets *r* or in any other convenient manner to the wheel-rim *f*.

In a further constructional form of the present invention (see Fig. 9) the tire lengths are secured in position on the wheel-rim *f* by means of screw-threaded studs or bolts *s*, which extend through holes in the wheel-rim and engage screw-threaded holes *v'*, provided in the plates *b*. In some instances it is preferable to insert in the elastic material rings *t*, (see Fig. 10,) having screw-threaded shanks *u*, extending through holes in the wheel-rim and secured therein by nuts *v*. The wires or rods *m*, embedded in the elastic material, are threaded through these rings *t*.

In some cases the lengths of tire are so arranged that the sides thereof toward their bases press against each other, as at *y*, Figs. 1 and 7. Each length thus supports the adjacent lengths and reduces the internal stresses in the india-rubber or like elastic material at the point where separation from the fastenings is most likely to occur, notably in cases where the india-rubber is vulcanized on a support of harder material.

The thickness of the elastic material toward the center of the tire lengths may be increased or other suitable methods of construction may be employed to avoid concavity of the tread of the tire and in order to produce a tire having a narrow central tread, it being noted that if flat tire lengths are employed the resulting tread would be hyperbolic in cross-section.

In order to prevent a vehicle provided with tires such as are hereinabove described slipping sidewise, the oblique grooves between adjacent tire lengths are preferably inclined in opposite directions on the wheels on opposite sides of the vehicle to which such tires are applied. In cases where the wheel is provided with only one detachable flange the lengths of tire are laid obliquely in such a direction that the driving stress tends to move them away from this flange. In other cases, as shown in Fig. 12, in order to further prevent skidding the lengths of material can be provided with transverse grooves 66, which when the said lengths are in position on the rim register with each other to form one or more circumferential grooves around the wheel. In the tire here shown the plates *b'* are dispensed with and the lengths of elastic material are held in position on the felly by a suitable number of rods 130

or wires *m*, extending longitudinally through the lengths of elastic material *a*. The ends of these rods or wires engage with grooves *d d* in the flanges *e e* in a similar manner to the plates *c*. (Shown in Fig. 3.)

Having described my invention, what I claim, and desire to secure by Letters Patent, is—

1. An elastic tire for vehicle-wheels, comprising a substantially cylindrical support, a series of lengths of elastic material, rigid carriers secured to the bases of said lengths of elastic material, projections on said rigid carriers, and separate lateral flanges on said support for engaging with said projections.

2. The combination with a vehicle-wheel felly or rim, of a series of lengths of elastic material arranged transversely around the periphery of said felly or rim, rigid carriers vulcanized to said lengths of elastic material, projections on said carriers extending from the ends of such lengths of elastic material, and separate recessed flanges on the sides of said felly or rim for engaging said projections.

25. 3. The combination with a vehicle-wheel felly or rim, of a series of lengths of elastic india-rubber arranged around the periphery of said felly or rim, rigid carriers for said lengths of india-rubber, two or more intermediate layers of india-rubber of greater hardness vulcanized to said lengths of elastic india-rubber and to said carriers the hardest intermediate layer being next to the carrier, and the softest intermediate layer next to the elastic india-rubber, and means for securing said carriers to said felly or rim.

4. The combination with a vehicle-wheel felly or rim, of a series of lengths of elastic india-rubber, rigid carriers for said lengths of elastic material, india-rubber of greater hardness vulcanized to said lengths of elastic india-rubber and to said carriers, means for securing said carriers to said rim or felly so that the said lengths of india-rubber abut against each other in such a manner that the joints between the different layers of india-rubber lie within the surface of contact between said lengths of india-rubber.

5. The combination with a vehicle-wheel felly or rim, of a series of lengths of elastic material each extending across the tread of the wheel and arranged obliquely around the periphery of said felly or rim so that two adjacent lengths are always in contact with the ground, rigid carriers secured to the bases of

said lengths of elastic material, projections on said carriers, and separate flanges on said felly or rim for engaging with said projections.

6. The combination with a vehicle-wheel felly or rim, of a series of separate lengths of elastic material which are arranged transversely around the periphery of said felly or rim and which each have a groove, said grooves registering with each other to form a circumferential groove around the tread of the tire, rigid carriers secured to the bases of said lengths of elastic material, projections on said carriers, and separate flanges on said felly or rim for engaging with said projections.

7. A tire-section, comprising a length of elastic india-rubber, a rigid carrier having parts projecting beyond said india-rubber, and two or more intermediate layers of india-rubber of greater hardness vulcanized to said lengths of elastic india-rubber and to said carrier, the hardest intermediate layer being next to the carrier and the softest intermediate layer being next to the elastic india-rubber.

8. An elastic tire for vehicle-wheels, comprising a rigid rim or felly, a series of lengths of elastic material, rigid carriers secured to the bases of said lengths of elastic material, projections on said rigid carriers, lateral flanges on said rim or felly for engaging with said projections, and means for uniting and detaching said flanges to and from each other.

9. The combination, with a vehicle-wheel felly or rim, of a series of lengths of elastic india-rubber arranged around the periphery of said felly or rim, rigid carriers for said lengths of india-rubber, india-rubber of greater hardness vulcanized to said lengths of elastic india-rubber and to said carriers, projections on said carriers extending from the ends of said lengths of elastic material, lateral flanges on said rim or felly for engaging said projections, and means for uniting and detaching said flanges to and from each other.

In testimony whereof I have hereunto set my hand in presence of two subscribing witnesses.

ARTHUR THOMAS COLLIER.
